WINTER FRONT FOR AUTOMOBILE RADIATORS

Mark W. Reeves, Poughkeepsie, N. Y.

Application April 1, 1933, Serial No. 663,919

2 Claims. (Cl. 257—132)

This invention relates to a winter front or 5 protector for the radiator of an automobile of that class which is intended to prevent freezing of the radiator in cold weather and control the passage of air through the radiator.

While devices for this purpose have been in use, they have been attached to the front face of the radiator in either a permanent or detachable manner, and have either been in the form 10 of a series of shutters, or fabric curtain which is unsightly and which has to be removed in warm weather.

One of the objects of the present invention is to provide a protector that may be used with the 15 present style of automobile where the radiator is constructed with a grill mounted in front of it for both protection and looks, and where the usual type of winter front can not be attached as these grills are either curved outward or are 20 V-shaped.

Another object of the invention is to provide a protector in the form of a curtain mounted upon a roller and located between the radiator core and the grid or grill, and which may either 25 be installed during the manufacture of the automobile, or afterward, and left in place during the hot weather, as it may be rolled up out of the way, and being constructed of metal similar to that used in tape lines it will not be affected 30 by weather conditions.

Another object of the invention is to provide means whereby the device may be readily attached to the radiators of cars, aeroplanes, tractors and in fact to any vehicle in which a water 35 cooling radiator is used.

Another object being to provide means whereby the device may be adjusted and held in place to cover any desired portion of the radiator, from the bottom upward.

Another object being to provide means whereby the device is held in a secure position to eliminate any noise or rattle.

With these and other objects in view, my invention consists in certain novel construction 45 and combination of parts as will hereinafter be fully described and claimed, and illustrated in the accompanying drawing which forms a part hereof, and in which like figures of reference refer to corresponding parts in all of the views, 50 and it is understood that slight changes may be made without departing from the spirit of the invention.

In the drawing:

Figure 1 shows the front elevation partly in 55 section of the grill and radiator of an automobile,

with my device in place between the front of the radiator core and the back of the grill.

Figure 2 is a horizontal cross section of the same, taken on the line 2—2 of Figure 1.

Figure 3 shows a partial section of the same, 60 enlarged to show details of construction, and the method of adjusting the protector and holding the same in place.

Figure 4 shows a vertical sectional view of Figure 1, to further illustrate the application of 65 the device.

Figure 5 shows a detail front elevation of the mounting frame for the curtain roller.

Referring to the drawing:

The usual radiator core is indicated by the 70 numeral 10, and to this is attached the grill 11, which is spaced from the core 10 and which is in many cases mounted at an angle to said core 10, and formed with the central rod 12 and a series of rods 13 so spaced apart as to form 75 openings 14 between the same, through which the air passes to and through the radiator core 10 for the cooling of the same; said radiator core 10 and grill 11 being mounted in some suitable manner upon the automobile frame 15; and it will be 80 noted that the bottom of the radiator core 10 does not extend as far down as the bottom of the grill, but stops just above the crank cap 16.

My device comprises a suitable frame, the size and shape of which will depend upon the make of 85 vehicle to which it may be secured, as these conditions will vary somewhat, but any suitable mounting means may be employed for the purpose of affording a frame 17 having outer end bearings 18, within which is rotatably mounted 90 the trunnions 19 of a roller 20; one of said trunnions 19 being freely rotatable within the bearing 18, and the other trunnion being flattened and prevented from rotation within the bearing, and attached to a spiral spring 21 mounted within the 95 roller 20 in the same manner as a shade roller, so that the curtain 22 is unrolled from the roller under tension, and when released will wind up upon said roller 20.

These bearing ends 18 may if desired be provided with guideways 23 extending upward along the front edges of the radiator core 10, and within which the edges of the curtain 22 may slide, and these guides 23 may be lined with some suitable material such as sponge rubber, felt, etc., but in 105 most cases it will be found that the curtain 22 does not require these guides 23.

It will be understood that this frame 17 and the guideways may be secured either to the radiator core 10 or to the lower inner part of the 110

grill 11 by any suitable means such as screws, clamps, etc., depending upon the shape and construction of both the radiator and the grill, and that this is not an essential part of the invention.

- 5 For raising and lowering the curtain 22, there is provided an operating rod 24 having its inner end secured to the face of the curtain adjacent the upper end thereof, and extending outward at right angles to said curtain, and between the 10 grill rod 12 and the adjacent rod 13, and the outer end of said operating rod 24 is provided with a knob or handle 25, by which the rod may be moved up or down within the slot or opening 14, to raise or lower the curtain 22, which is in contact with the face of the radiator core 10.

15 The mounting frame 17 is formed as here shown with the ears 31 having holes 30 for the bolts 29 that pass through the radiator core 10 and mount the frame thereto.

- 20 To prevent noise of the operating rod 24 and to retain the same in place and the curtain in an adjusted position against the tension of the spring 21 within the roller 20, there is provided a tension locking device on the rod 24, which comprises a spiral spring 28 loosely mounted thereon with one of its ends in contact with a washer 26 which is in contact with and slides against the rear faces of the bar or grill rod 12 and the rod 13, while the rear end of said spring 25 contacts 25 with a boss 27 on the curtain 22 to which the rod 24 is attached.

30 This spring 25 thus forces the rod 24 inward and retains the curtain 22 in contact with the radiator core 10 at all times, and at the same time 35 produces friction between the washer 26 and the rods 12 and 13, thus holding the rod 24 wherever it is placed and retaining the curtain 22 at any desired height.

35 Should a more positive locking means be desired, the rod 13 may be provided with a series

of notches or teeth in which the rod 24 may be engaged, or if desired the curtain 22 may be raised and lowered by a cable attached to the upper edge thereof, threaded through the radiator core 10, over a pulley and to the dash of the vehicle to be operated by the driver.

80 It will be understood that the curtain is to be made of metal or other suitable material, and that the same may be mounted in front of a radiator where no grill is used.

85 Having thus described my invention, what I claim as new and desire to secure by Letters Patent, is:—

1. In a radiator protector, the combination with the radiator core and a grill spaced therefrom and formed with vertical openings therein, and having a frame mounted between said core and the grill and secured to the core adjacent the lower end thereof, a spring actuated roller mounted in said frame, and a flexible curtain mounted thereon, of an actuating rod secured to said curtain and extending through one of the vertical openings in the grill for the purpose of moving said curtain, and a tension spring mounted on said rod between the curtain and the grill.

90 2. In a radiator protector, the combination with the radiator core and a grill spaced therefrom and formed with vertical openings therein, and having a frame located between said core and the grill and attached to the core, and a 95 spring actuated roller having a curtain thereon and mounted in said frame and adapted to be unrolled against said core, of a rod attached to said curtain and extending through one of the openings in said grill, and a locking device 100 mounted upon said rod comprising a coil spring mounted on said rod between the curtain and the grill to retain the curtain in an adjusted position.
